INVENTOR
Frank M. Ashley

UNITED STATES PATENT OFFICE.

FRANK M. ASHLEY, OF BROOKLYN, NEW YORK

VALVE.

Application filed April 8, 1926. Serial No. 100,503.

My invention relates to valves.

The object of my invention is to provide a valve construction that will have long life and will not leak.

5 Further objects of my invention and advantages derived from my construction will be set forth in the following specifications.

Referring to the drawings forming a part of the specifications:

10 Fig. 1 is an elevational sectional view of a construction illustrating my invention.

Fig. 2 is a plan sectional view taken on line 2—2 of Figure 1.

15 Fig. 3 is a longitudinal sectional view of a fragment of a modification of the construction illustrated in Figure 1.

Fig. 4 is a longitudinal sectional view of a construction illustrating another form embodying my invention.

20 Fig. 5 is a plan view partly in section, taken on line 5—5 of Figure 4.

A, indicates the body portions of the valve constructions, B, a primary or buffer valve, and C, the secondary valve. A' indicates 25 the inlet and A² the outlet openings of the valve body. The present constructions comprise a globe valve and plug valve combination, the body portion A being formed like a globe valve, and having its upper 30 central portion extended and provided with a conically shaped bore C' in which the plug portion C fits in the usual manner. The plug C is provided with a central bore C² which serves as a conduit from its lower 35 end to the port C³ formed in its wall and opening to the outlet A², and its upper end is provided with a conical surface C⁴. A valve stem D, is provided with a conical shaped bearing surface D' which fits in 40 tight sliding relation with the surface C⁴ to provide a metal seat stuffing box. The stem is provided with a threaded bore D² in its lower end to engage the threaded stem B' of the valve B. To prevent the valve B 45 from rotating a square lug B² is formed on its under side integral therewith and engages with a square shaped recess E' formed in the bottom cap E; said cap E serving as a closure for the opening A³ 50 formed in the bottom of the body A. A spring F is interposed between the under side of valve B and the cap E to support the valve B. Channels G are formed in the wall of the body A for oil, and similar chan-

nels may be formed in the plug, as indicated 55 in Figure 4 as G', and in this construction they may be so placed relatively as to form a single channel or oil reservoir by means of which the plug may be lubricated.

The plug is rotated by means of a lever 60 H which may be formed integral therewith as shown in Figure 4, or may be separable therefrom as shown in Figure 1, whereby the lever may be set to extend in any desired direction and to permit of this adjustment the top end of the plug is provided with teeth like those formed on a spur gear, and indicated by I and spaced entirely around the top end in a circle, and the lever is provided with corresponding teeth to engage the teeth I, therefore by raising the lever above the end of the plug, it may be turned relative to the plug and then lowered into engagement as shown, and with the handle H extending in any desired direction, as will be readily understood.

It will be observed that there is a difference in the constructions shown in Figures 1, 3 and 4.

In Figures 1 and 3 the widest part of the 80 plug is located at the lower end of the body A, whereas in Figure 4, the widest part of the plug is located at the upper end of the body, and the plug is removed through the top opening of the bore C' instead of 85 through the opening A³ in the bottom end of the body portion. In Figure 1 the primary valve B seats directly against the lower end J' of the inner casing J, and when open, the pressure of the fluid passing through, tends to seat the plug. By removing the handle K, and cap E, the entire working parts may be removed from the body A. On the other hand, the construction of Figure 4 permits the plug to be removed while 90 the valve B holds the pressure from the inlet side A', for inspection or relief on the discharge side of the line. In Figure 4, the plug is provided with a pin L, which extends laterally directly over a ring M which is connected by a thread M' to the body A, and should the plug stick in its seat, it may be lifted by screwing the cap M upward in contact with the pin to release the excessive 95 friction between the plug and body.

It will be noted that the thickness of the wall of the plug is practically even throughout and therefore the expansion and contraction

due to changes in temperature, will not cause the plug to stick in the body portion.

In Figure 3, I illustrate a construction in which the valve B seats directly against the lower end of the plug instead of against the under side of the casing. This construction is cheaper to make and suitable for low pressure work.

Many other modifications may be made without departing from the invention disclosed as will be at once apparent to those skilled in this art.

The valve B may be removed for repairs and the plug valve used alone if necessary. The large area of contact surface between the plug and body assures a maximum of wear and as only one port is used in the plug it is easy to keep it lubricated.

The greatest advantage is that two separate valves co-operate to hold a tight joint and that the wearing surface of the plug is never exposed to the fluids passing through the valve and therefore the scouring action of steam or other fluids do not injure the surfaces relied upon to keep a tight joint. The valve is operated as follows:

Assuming both valves to be closed, first open the plug valve by turning the lever H until the port C³ is in perfect open communication with the outlet A²; then open valve B by turning the handle K as is done with the standard globe valve. All of the scouring action is taken by valve B. In closing, first close valve B and then the plug valve. It is clearly evident that valve B takes the hard wear, and even though it may soon leak, the plug valve holds tight, and since the valve B may easily be re-ground or replaced, the valve as a whole will have long life and hold high pressures safely.

Having thus described my invention I claim as new:

45 1. A valve construction comprising a body portion having a conduit with an inlet and an outlet, and an opening in the bottom thereof; a bottom cap, a disc valve to serve as a buffer valve located on the inlet or 50 pressure side of the valve and a plug of less diameter than the buffer valve located above the disc valve to provide a tight joint and removable thru said opening in the bottom, and means by which said buffer valve 55 may be opened after said plug valve is opened and closed before said plug valve is closed in operating the construction, and means for preventing the rotation of the disc valve.

60 2. A valve comprising a body portion having a bottom opening and a conduit and two ports formed therein, a buffer valve for closing one port and a plug valve of less diameter than the buffer valve for closing 65 the other port, said plug valve having a

bore thru which the stem of the buffer valve projects, a handle for each of said valves, both of said valves being simultaneously removable thru said opening, a cap for said opening and coacting means for preventing the rotation of said buffer valve.

3. A valve comprising a body portion having a conduit and two ports formed therein, a buffer valve for closing one port and a conical plug valve for closing the other port, said plug valve having a bore through which the stem of the buffer valve projects, a handle for each of said valves, a cap having means for preventing the rotation of the buffer valve and a spring located below the buffer valve to assist in seating the valve.

4. A valve comprising a body portion having an inlet and an outlet and a conduit leading therethrough, a buffer valve and a plug valve controlling said conduit, said plug valve having a bore with a conical surface, said buffer valve having a stem with a conical surface to fit the surface in the bore of the plug valve, means for preventing the rotation of the buffer valve, means whereby said valves may be independently operated.

5. A valve construction embodying a body portion having a conduit therein, and a bottom opening, a cap for said opening, two valves one of which is a disc of relatively large diameter and serves as a buffer valve and the other of which is a plug and serves to present a tight joint, both of which are simultaneously removable from the body portion thru said bottom opening and both of which are pressed against their seats by the fluid pressure controlled thereby.

6. A valve construction embodying a body portion having a conduit therein and a bottom opening, a bottom cap, and two valves controlling said conduit, one of which serves as a buffer valve and the other of which serves to hold a tight joint, both being removable from the body portion through said bottom opening, and co-acting means between said bottom cap and buffer valve to prevent rotation of the latter.

7. A valve comprising a body portion having a conduit and a bottom opening, a plug valve of less diameter than that of said opening controlling said conduit, a buffer valve seated against the body portion below said plug valve and removable with the plug valve from the body portion thru said bottom opening, and a cap for said opening.

8. A valve comprising a body portion having a conduit and a bottom opening, a conical plug valve controlling said conduit, a buffer valve of greater diameter than the plug valve seated against the body portion and controlling said conduit, and removable from the body portion through said bottom opening together with the plug valve, and a

cap for said opening formed to co-act with said buffer valve to prevent rotation of the latter.

9. A valve construction combining a plug valve and a globe valve comprising a body portion having an upper and a lower valve port formed therein, and having an opening in the bottom of the casing, and having an opening in the top of the casing; a conical plug valve fitted in the upper side of the casing and controlling the upper outlet port, and having an inlet passage formed in its lower end; and having a valve stem extending therefrom thru said top opening, a lever 5 connected to said stem for turning said plug; a disc valve of larger diameter than the lower port and the adjacent end of the plug valve, and means extending thru said plug and stem to operate said disc valve, a cap for 10 said lower opening, and means cooperative with said disc valve and cap to prevent rotation of said valve, said valves being removable thru the bottom opening.

10. A valve construction combining a plug valve and a globe valve comprising a body portion having an upper and a lower valve port formed therein, and having an opening in the bottom of the casing, with a cap to close said opening, and having an opening 25 in the top of the casing; a conical plug valve fitted in the upper side of the casing and controlling the upper outlet port, and having an inlet passage formed in its lower end; and having a valve stem extending therefrom thru said top opening, a lever connected to said stem for turning said plug; a disc valve of larger diameter than the lower port, and the adjacent end of the plug valve located below said port and controlling same, 30 and means extending thru said plug and stem to operate said disc valve, and means cooperative with said disc valve and cap to prevent rotation of said valve, said valve being removable thru the bottom opening 45 without removing the said means used for operating said valve said plug having a cir-

cumferential groove formed in its lower end, and packing in said groove which also serves as a seat for said disc valve.

11. A plug and globe valve combination comprising a body portion having an inlet and outlet in alignment and an upper and lower valve port formed therein and an opening in the bottom and top of the casing, a cap for said bottom opening, a conical 50 plug fitted in the upper side of the casing and controlling said upper outlet port and having an inlet passage in its lower end, and having a valve stem extending therefrom thru said top opening, a lever for said stem, a disc valve of larger diameter than the adjacent end of the plug, located below said port and controlling same, means extending thru said plug and stem to directly operate said disc valve, and means cooperative with 55 said cap to prevent rotation of same, said valves being removable through said bottom opening.

12. A plug and globe valve combination comprising a body portion having an inlet 70 and outlet in alignment and an upper and lower valve port formed therein and an opening in the bottom and top of the casing, a cap for said bottom opening, a conical plug fitted in the upper side of the casing 75 and controlling said upper outlet port and having an inlet passage in its lower end, and having a valve stem extending therefrom thru said top opening, a lever for said stem, a disc valve of larger diameter than the adjacent end of the plug, located below said port and controlling same, means extending thru said plug and stem to directly operate said disc valve, and means cooperative with 80 said cap to prevent rotation of same said plug having a circumferential groove formed in its lower end and packing in said groove extending to the lower end of said plug.

In testimony whereof I have affixed my signature.

FRANK M. ASHLEY.
